(57) **CLAIM**

The ornamental design for electronic device, as shown and described.

DESCRIPTION

FIG. 1 is a perspective view of an electronic device showing our new design;

FIG. 2 is a front side view thereof;

FIG. 3 is a rear side view thereof;

FIG. 4 is a left side view thereof;

FIG. 5 is a right side view thereof;

FIG. 6 is a top plan view thereof;

FIG. 7 is a bottom plan view thereof;

FIG. 8 is another perspective view thereof, showing the design in a slide-out position; and,

FIG. 9 is still another perspective view thereof, showing the design in a tilt position.

The broken line showing of a keypad in FIGS. 8 and 9 is included for the purpose of illustrating portions of the article and forms no part of the claimed design.

1 Claim, 9 Drawing Sheets
